UNITED STATES PATENT OFFICE.

EVERETT L. SHAIN, OF CROWN HILL, WEST VIRGINIA.

RAIL-BOND.

1,199,620.

Specification of Letters Patent. Patented Sept. 26, 1916.

Application filed October 7, 1914. Serial No. 865,549.

To all whom it may concern:

Be it known that I, EVERETT L. SHAIN, a citizen of the United States, residing at Crown Hill, in the county of Kanawha and 5 State of West Virginia, have invented new and useful Improvements in Rail-Bonds, of which the following is a specification.

The present invention relates to an electric bond for railway rails, and the primary 10 object of the invention is to produce an article of this character which shall be securely connected with the rails and sustained thereon by a conductor or bond member whereby an electric connection between 15 the rails is assured.

With the above and other objects in view, the improvement resides in the construction, combination and arrangement of parts set forth in the following specification and falling 20 within the scope of the appended claims.

In the drawing: Figure 1 is a perspective view showing two rails bonded in accordance with the present invention, Fig. 2 is a detail sectional view taken through one of 25 the clamping members and its securing bolt, Fig. 3 is a detail perspective view of one of the clamps, and Fig. 4 is a reduced sectional view on the line 4-4 of Fig. 3.

Referring now to the drawing in detail, 30 R-R designates the meeting ends of two railway rails of the ordinary construction.

Arranged upon the base flange of each of the rails is a clamp 2. Each of the clamps comprises a horizontally straight base 3 having an enlarged outer end or head 4 which is integrally formed with an inwardly angularly extending jaw 5. The angular extension 5 with relation to the straight base 3 permits of the clamps being forced 40 into tight engagement one with each of the base flanges of the rails. The head 4 of each of the clamps is provided with a longitudinally arranged opening 6 and the base 3 has its underside formed with a channel 45 in a line with said opening as indicated by the numeral 7.

The numerals 9 designate hook members which are formed with longitudinally extending threaded shanks 8, the said hooks 50 each engaging with the longitudinal flanges of the rails opposite that engaged by the clamps, while their shanks 8 are arranged within the channels 7 and have their threaded ends passed through the openings 6 of 55 the said clamps. The heads 4 have their outer faces, above the opening 6 provided

with transversely arranged grooves 14, the inner walls of the said grooves being rounded and providing seats for a longitudinally extending straight bond wire 15. The wire 60 is preferably of a greater width than the depth of the groove 14 and so slightly projects beyond the grooves and beyond the straight faces of the heads 4.

The numerals 15 designate washers which 65 are passed over the extending ends of the shanks 8 of the hooks 9 while the said shanks also receive the coiled ends 10 provided upon a curved clamp connecting member 11.

12 designates bolts which are screwed 70 against the eyes 10 of the connecting member 11 which force the coiled or rounded ends 10 of the member 11 tightly against the washer and consequently the washer 75 tightly against the bond 15.

By constructing the connecting member 11 of a curved wire it will be noted that the clamps will not be influenced by a movement of the rails at the meeting ends thereof, and further the conductor 15 is of a sufficient 80 length to give in a longitudinal direction without becoming disconnected from the clamps or losing its efficiency. The clamps are, of course, constructed of some electric 85 conducting material, such as copper and likewise the connecting member 11 may be also constructed of some conducting material, so that said member 11 will serve as an additional bond between the rails. A washer 16 may be arranged upon the shanks 90 of the bolts to contact with the outer faces of the curved ends of the connecting member 11, and the nuts 13 may bear against the said washer 16. The construction is such 95 that the spacing member 11 will retain the clamps in proper relation with each other against danger of sliding longitudinally of the rails. The conductor 15 may be applied to be removed from the grooves 14 without entirely separating the nuts 12 from the threaded shanks 8 of the hook members, and the washer members 16 being flat and round 100 in plan may be permitted to rotate or revolve upon the shanks of the hooks without permitting the conductor member 15 leaving the seats 14 and also the said washers being comparatively thin will be readily compressed against the member 15.

From the above description, taken in connection with the accompanying drawing, the 110 simplicity of the device as well as the advantages thereof will, it is thought, be perfectly

apparent to those skilled in the art to which such invention appertains without further detailed description.

Having thus described the invention, what I claim is:

1. The combination with alining rails and clamp members having bolts securing the same to the edges of the flanges of the rails, and said clamps having their outer faces provided with grooves, of a flexible bond member received in the grooves and projecting therethrough, a washer upon each of the bolts contacting with the said bond, and nuts threaded on the bolts engaging with the washers to force the same against the bond to compress the latter in the grooves.
2. The combination with two connected rails, clamps arranged on the edges of the flanges of the rails and bolts securing the

clamps to the said rails, the said clamps having registering depressions which are of a depth greater than a half circle, a flexible bond wire arranged in the grooves and projecting therethrough, a washer upon each of the bolts contacting with the bond, a wire spacing member having its ends formed with eyes which are received in the bolts and nuts threaded upon the bolts contacting with the said eyes to force the same into engagement with the washers to cause the latter to press the bond against the walls of the grooves.

In testimony whereof I affix my signature in presence of two witnesses.

EVERETT L. SHAIN.
